UNITED STATES PATENT OFFICE.

WELBY POWELL, OF SEWELLTON, KENTUCKY.

SHOWER-BATH VALVE.

Application filed August 11, 1921. Serial No. 491,471.

To all whom it may concern:

Be it known that WELBY POWELL, a citizen of the United States of America, residing at Sewellton, in the county of Russell 5 and State of Kentucky, has invented new and useful Improvements in Shower-Bath Valves, of which the following is a specification.

The object of the invention is to provide a 10 shower bath valve whereby the flow of hot and cold water may be jointly controlled to provide for any desired temperature of shower, and whereby a graduated or progressively varying temperature may be provided either from hot to cold or from cold to 15 hot at the option of the operator at a rate of variation which may be regulated to suit the preference of the bather; and with these objects in view the invention consists in a 20 construction and combination of parts of which a preferred embodiment is shown in the accompanying drawings, wherein:—

Figure 1 is a side view of a valve embodying the invention.

Figure 2 is a vertical sectional view of the same.

Figure 3 is a plan view.

Figure 4 is a horizontal section on the plane indicated by the line 4—4 of Figure 2.

Figure 5 is a horizontal section on the plane indicated by the line 5—5 of Figure 2.

The cold and hot water supply pipes are 35 indicated respectively at 10 and 11 with the valve located at the junction thereof and consisting essentially of a valve chamber 12 in which is arranged the tubular valve member 13 mounted for rotary and reciprocatory 40 movement and having side ports 14 and 15 for respective registration with the inlet ports from the supply pipes and which are shown respectively at 16 and 17. The spray nozzle 18 which may be of any preferred 45 construction is arranged in communication with the valve chamber 12 and the ports of the valve member 13 are so arranged longitudinally, or in the direction of sliding or reciprocatory movement of the said valve 50 member, with relation to the chamber or casing ports 16 and 17 that the former may be in communication respectively with both of the latter but not in registration therewith. When one of the valve ports is in 55 complete or full registration with one of the

casing ports the other valve port is entirely out of communication with the other casing port in any relative position of the parts, and when the valve member is moved longitudinally or in the path of its axis from such extreme position to effect the opening of the other port, the exposure of the latter will be effected gradually until about one-half of the area thereof is exposed at which time only one-half of the first named port will be exposed, the exposure of the first-named port having been reduced gradually as the exposure of the second-named port was increased. From this midway position the further movement of the valve in the same direction will involve a further increase in the exposure of the second-named port and a reduction in the exposure of the first-named port, until the second-named port is fully exposed and the first-named port is completely closed. While obviously this arrangement may be accomplished in different ways the arrangement illustrated in the drawing contemplates the disposal of the casing ports 16 and 17 in diametrically opposite relations or in transverse registration while the valve ports 14 and 15 are disposed in longitudinally spaced relation and at such a divergence longitudinally of the path of the valve that when for example the valve port 15 is in complete flow and direct registration with the casing port 17 the valve port 14 is entirely out of communication with the casing port 16. Thereupon the downward movement of the valve member tending to open the cold water casing port 16 will involve a gradual cutting off or closing of the hot water casing port 17 and this movement respectively in opening and closing the ports will continue until equal values or areas of each of the casing ports 16 and 17 are exposed so that there is admitted to the casing or valve chamber equal quantities of hot and cold water, assuming of course that the supplies of the water from the hot and cold water sources are under equal pressures. From this midway position the further forward or progressive movement of the valve member will gradually close the casing port 17 and continue to progressively open the casing port 16 until a full opening of the latter has been reached when the casing port 17 will be completely closed.

Therefore starting with the elements of the structure as so far described in the posi-

tion indicated in Figure 1 and as above described and moving the valve member gradually downward it will be obvious that the temperature of the water supplied to the nozzle will first be entirely from the supply pipe 11 and hence will be hot and the temperature will, therefore, be gradually modified or reduced until it reaches an intermediate temperature due to the mixture of equal quantities of the hot and cold water and thence will further be reduced until the supply is entirely from the cold water pipe, the hot water supply being completely cut off.

15. The valve member 13, however, is revolvably fitted in the valve chamber or seat so that with the ports thereof in communication with both casing ports at any desired or preferred adjustment longitudinally, so as to expose to the desired relative extent the hot and cold water casing ports so that the temperature of the mixture is exactly that desired by the operator, the volume of supply to the nozzle may be diminished by turning the valve so as to equally cut off or reduce the exposure of both casing ports. This reduction can be continued by the turning of the valve member until only a very small supply is admitted to the valve chamber.

20. Again with the parts in the position indicated in Figure 2 wherein the valve member is at the upper limit of its stroke or movement and with the valve port 15 in communication with the casing port 17, it will be obvious that by turning the valve member through an angular distance of say ninety degrees the hot water port can be entirely closed and therefore the supply of water to the valve chamber cut off. Again by continuing the rotary movement of the valve member through an angular distance of ninety degrees the valve port 15 may be arranged in registration with the cold water casing port 16 and thereupon a downward movement of the valve member will cause a gradual closing of the cold water port and the gradual opening of the hot water port through the communication of the valve port 14 with the casing port 17, so that the temperature of the water supplied to the nozzle will be gradually raised until it reaches the temperature of that in the hot water supply pipe.

25. In the illustrated embodiment of the invention the valve member is provided with a stem 19 provided at its upper end with a piston 20 operating in a cylinder 21, and pivotally connected with the stem is a lever 22 fulcrumed at an intermediate point of its length in a slot 23 formed in a bracket 24 which is swiveled upon a journal 25 so that by means of the lever and by swinging the same laterally or horizontally in one direction or the other the stem may be rotated to 30 turn or reverse the valve member 13. Pref-

erably the outer or free end of the lever 22 is provided with a counterweight 26. The longitudinal movement of the valve member in its seat or chamber may be effected by vertically swinging the lever 22, or other means for effecting such operation may be provided, and similarly the rotary movement of the valve member may be effected by means of said lever to either modify the volume of supply of the water after the desired temperature has been secured, or to reverse the position of the valve as above described.

Under certain conditions, however, it may be desired that the gradual variation in the temperature of the water either from hot to cold or from cold to hot be accomplished mechanically or automatically, or without relying upon the manual movement or adjustment of the parts as above described, and to this end the stem 19 is made of tubular form, as shown, in communication at its lower end with the interior of the valve chamber and in communication at its upper end with the cylinder 21 above the piston 20, and this by-pass formed by the bore of the stem is fitted with a controlling or by-pass valve 27, adapted to remain closed when the operation of the valve is to be conducted manually and provided with an operating handle or stem 28 whereby it may be opened to any desired extent. With the main or supply valve member 13 in a position exposing either of the casing ports so as to admit water from either of the supply pipes to the valve chamber, the opening of the by-pass valve will allow water incident to the pressure in the valve chamber to pass upward through the by-pass or tubular stem into the cylinder 21 and thereby depress the piston 20 and consequently the main or supply valve so as to gradually advance the latter downwardly to vary the relative extents of opening of the casing ports in the manner described hereinbefore in the progressive variation of the temperature, and this progressive movement may be utilized to modify the temperature of the water supplied to the nozzle by raising or lowering the temperature, according to the annular or rotary position of the main or supply valve or in other words according to whether the operating lever 22 is at one limit or the other of its horizontal path of movement. By varying the extent of opening of the controlling or by-pass valve, it will be obvious that the progressive movement downwardly of the main or supply valve may be modified in rate of speed from a very slow movement to one as rapid as may be desirable to the bather.

Thus, through the operation of the tubular valve 13 it is possible to cut off all supply or flow of water, to draw either hot or cold water alone, in a graduated volume, from

full head to a small stream, to draw from both sources of supply at any desired relative degree of opening of the ports to produce the desired temperature and with any desired volume of flow, and to gradually and progressively modify the temperature either upwardly or downwardly at any desired rate of modification. Owing to the fact that the mounting of the valve 13 makes it rather difficult to secure a water tight or non-leaking seating thereof, it is preferable to employ an auxiliary cut off to supplement the main valve when a flow of water is not required and, therefore, a conical plug 29, concentric with the main valve is arranged in a conical seat in the casing 30,—being held seated by spring 31, the valve chamber 12 consisting of the bore of said valve plug and the ports 16 and 17 being formed in the wall thereof and being registrable with similar ports 16^a and 17^a in the casing 30, so that the turning of the plug effectually cuts off the supply. The nozzle may be carried by the plug to form a handle.

In the illustrated embodiment of the invention the bracket 24 as above described is swiveled upon a journal 25 which may be formed as illustrated by a tubular extension of the valve plug 29, the bore therein serving as a means of receiving the tubular stem 19 of the piston 20, and said bracket is held in place by means of main and jamb nuts 32 and 33 threaded upon the journal while the upper end of the latter is covered by a packing cap 34 as a means of preventing leakage from the valve chamber.

Having described the invention, what is claimed as new and useful is:—

1. A valve mechanism comprising a casing provided with ports for connection respectively to hot and cold water supply pipes, a valve operatively mounted in said casing and ported to expose in either of its extreme open positions one or the other of the ports in said casing and in intermediate position to expose both ports, and means actuatable by pressure in the valve casing for effecting progressive movement of the valve member.

2. A valve mechanism for cooperating telescoped elements consisting respectively of a longitudinally and rotatably movable hollow laterally ported valve member and a laterally ported valve chamber of which the ports are respectively connected with hot and cold water sources of supply, the ports of one of said members being offset in one direction with relation to the ports of the other, and means actuatable by pressure in the valve chamber for effecting progressive movement of one of said members relative to the other.

3. A valve mechanism for cooperating telescoped elements consisting respectively of a longitudinally and rotatably movable hollow laterally ported valve member and

a laterally ported valve chamber of which the ports are respectively connected with hot and cold water sources of supply, the ports of one of said members being offset in one direction with relation to the ports of the other, and means actuatable by pressure in the valve chamber for effecting progressive longitudinal movement of one of said members relative to the other.

4. A valve mechanism for cooperating telescoped elements consisting respectively of a longitudinally and rotatably movable hollow laterally ported valve member and a laterally ported valve chamber of which the ports are respectively connected with hot and cold water sources of supply, the ports of one of said members being offset in one direction with relation to the ports of the other, and an actuating device consisting of a cylinder and piston of which the latter is in valved communication with the valve chamber and one of which is connected with one of said members.

5. A valve mechanism for cooperating telescoped elements consisting respectively of a longitudinally and rotatably movable hollow laterally ported valve member and a laterally ported valve chamber of which the ports are respectively connected with hot and cold water sources of supply, the ports of one of said members being offset in one direction with relation to the ports of the other, an actuating mechanism consisting of a cylinder and piston of which a hollow piston rod is in communication with the valve chamber for communicating pressure to the cylinder, and a valve controlling the passage of pressure through said piston rod.

6. A valve mechanism for cooperating telescoped elements consisting respectively of a longitudinally and rotatably movable hollow laterally ported valve member and a laterally ported valve chamber of which the ports are respectively connected with hot and cold water sources of supply, the ports of one of said members being offset in one direction with relation to the ports of the other, and a valve member actuating means consisting of a cylinder and piston, a hollow piston rod connecting the piston with the valve member and forming a means of communication between the valve chamber and the cylinder, and a valve for controlling the communication through said piston rod.

7. A valve mechanism for cooperating telescoped elements consisting respectively of a longitudinally and rotatably movable hollow laterally ported valve member and a laterally ported valve chamber of which the ports are respectively connected with hot and cold water sources of supply, the ports of one of said members being offset in one direction with relation to the ports

- of the other, and a valve member actuating means consisting of a cylinder and piston, a hollow piston rod connecting the piston with the valve member and forming a means of communication between the valve chamber and the cylinder, and a valve for controlling the communication through said piston rod, and means for turning the piston rod to rotatively vary the relation of the ports of the valve member and chamber.
8. A valve mechanism for cooperating telescoped elements consisting respectively of a longitudinally and rotatably movable hollow laterally ported valve member and a laterally ported valve chamber of which the ports are respectively connected with hot and cold water sources of supply, the ports of one of said members being offset in one direction with relation to the ports of the other, and a valve member actuating means consisting of a cylinder and piston, a hollow piston rod connecting the piston with the valve member and forming a means of communication between the valve chamber and the cylinder, and a valve for controlling the communication through said piston rod, an operating lever connected with said piston rod, and a bracket swiveled
- 15 of the other, and a valve member actuating means consisting of a cylinder and piston, a hollow piston rod connecting the piston with the valve member and forming a means of communication between the valve chamber and the cylinder, and a valve for controlling the communication through said piston rod, an operating lever connected with said piston rod, and a bracket swiveled
- 20 of the other, and a valve member actuating means consisting of a cylinder and piston, a hollow piston rod connecting the piston with the valve member and forming a means of communication between the valve chamber and the cylinder, and a valve for controlling the communication through said piston rod, an operating lever connected with said piston rod, and a bracket swiveled
- 25 of the other, and a valve member actuating means consisting of a cylinder and piston, a hollow piston rod connecting the piston with the valve member and forming a means of communication between the valve chamber and the cylinder, and a valve for controlling the communication through said piston rod, an operating lever connected with said piston rod, and a bracket swiveled

in axial alignment with the valve member and forming a fulcrum for said lever. 30

9. A valve mechanism for cooperating telescoped elements consisting respectively of a longitudinally and rotatably movable hollow laterally ported valve member and a laterally ported valve chamber of which the ports are respectively connected with hot and cold water sources of supply, the ports of one of said members being offset in one direction with relation to the ports of the other, and a valve member actuating 40 means consisting of a cylinder and piston, a hollow piston rod connecting the piston with the valve member and forming a means of communication between the valve chamber and the cylinder, and a valve for controlling the communication through said piston rod, an operating lever connected with said piston rod, and a bracket swiveled in axial alignment with the valve member and forming a fulcrum for said lever, the 45 lever being counterweighted to yieldingly maintain the valve member at one limit of its longitudinal movement.

In testimony whereof he affixes his signature.

WELBY POWELL.
